UNITED STATES PATENT OFFICE.

LEO FEBRE, OF NORFOLK, VIRGINIA.

LOADER.

1,247,805.

Specification of Letters Patent. Patented Nov. 27, 1917.

Application filed August 14, 1917. Serial No. 186,196.

To all whom it may concern:

Be it known that I, LEO FEBRE, a citizen of the United States, residing at Norfolk, in the county of Norfolk and State of Virginia, have invented a new and useful Loader, of which the following is a specification.

One object of this invention is to provide novel means whereby a vehicle, such as the tender of a locomotive, may be supplied with coal and water while the train of which the tender constitutes a part is in motion.

Another object of the invention is to provide novel means for controlling the closures for the coal pocket and the water tank of the car which supplies the commodities above named to the tender of the locomotive engine.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in top plan a device constructed in accordance with the present invention, the tender of the locomotive engine being omitted.

Fig. 2 is a side elevation showing the dispensing car mounted on the tracks which the car traverses.

Fig. 3 is a side elevation showing the dispensing car and the tender, the parts being in the positions which they assume just prior to the releasing of the closures on the car which permits the coal and water to be deposited in the tender.

Fig. 4 is a cross section on the line 4-4 of Fig. 3.

Fig. 5 is a top plan of the tender.

Fig. 6 is a cross section on the line 6-6 of Fig. 3.

Fig. 7 is a top plan of the dispensing car.

Fig. 8 is an elevation showing the opposite side of the tender from that delineated in Fig. 3, the view being introduced for the

purpose of showing the tender-carried mechanism whereby the closures for the coal pocket and the water tank are released.

Fig. 9 is a fragmental side elevation showing the keeper which is carried by the front part of the water tank.

The numeral 1 indicates the rails of a railroad track. Towers 2 are erected along the side of the track. The towers 2 support a top rail 3 and a bottom rail 4, constituting an auxiliary track, the rails 3 and 4 being in vertical alignment. The auxiliary track 3-4 is located above the railroad track 1, and one end of the auxiliary track curves away from the railroad track 1 as shown at 5 in Fig. 1. This laterally deflected end 5 of the auxiliary track 3-4 may be of any desired length.

The numeral 6 denotes a vehicle, such as a locomotive tender, adapted to traverse the railroad track 1. The tender 6 has a forward coal compartment 7 and a rear water compartment 8. The water compartment 8 is closed by a top 9 having an opening 10. A flange 11 upstands from the sides and the end of the tender 6. The side portions of the flange 11 are connected by a cross wall 12 which, together with parts of the sides of the flange 11, and the rear end of the flange, forms a box 13 about the opening 10.

When water is discharged into the box 13, the water runs through the opening 10 into the compartment 8. One side portion of the flange 11 on the tender 6 carries an upstanding wing 14. The wing 14 has a front projection 15 and a rear projection 16, both of which extend upwardly. A lever 17 is fulcrumed at 18 on one side of the tender 6. The handle end 19 of the lever extends forwardly, and is resilient, so that it may be engaged either with the upper end of a keeper 20 projecting from the tender, or with the lower end of the keeper. A releasing rod 21 slides vertically in an opening 22 in one side portion of the flange 11 on the tender 6. The upper end of the releasing rod 21 upstands above the wing 14, and the lower end of the releasing rod is pivoted at 23 to the rear end of the lever 17.

When the handle end 19 of the lever 17 is engaged with the lower end of the keeper 20, the releasing rod 21 will be elevated, and when the handle end of the lever is engaged with the upper end of the keeper, the releasing rod 21 will be depressed.

The numeral 24 denotes a dispensing car mounted to move along the auxiliary track 3-4. At its bottom, adjacent its ends, and intermediate its ends, the car 24 carries depending lower arms 25. Grooved wheels 26 are journaled on the arms 25 and traverse the bottom rail 4. The car 24 is provided at its upper edge, with upstanding arms 27 located at the ends of the car and intermediate the ends of the car. Grooved wheels 28 are journaled on the arms 27 and coöperate with the top rail 3. The car 24 has a cross wall 29 forming a coal pocket 30 at the forward end of the car and a water tank 31 at the rear end of the car. The water tank 31 is closed by a top 32 having an opening 33 controlled by a removable closure 34. The water tank 31 may be filled through the opening 33. The coal pocket 30 is provided with a vertically swinging bottom or chute 35 hingedly connected at 36 with a fixed inclined bottom 69 constituting a part of the coal pocket. The bottom or chute 35 has side wings 37 operating exteriorly of the coal pocket. The chute 35 is mounted to swing vertically, in a direction at right angles to the line of advance of the car 24. The numeral 38 denotes a vertically swinging closure for the front of the coal pocket 30. The vertically swinging closure 38 operates between the side wings 37 of the chute 35 and is hinged at 39 to the body portion of the car 24. The vertically swinging closure 38 has side wings 40 which lie within the coal pocket 30, as indicated in Fig. 4, when the member 38 is in a depending, closed position. A keeper 41 is attached to the vertically swinging closure 38 and depends below the lower edge of the closure. The keeper 41 has a notch 45 in one edge. A latch 42 is pivoted at 43 to the lower face of the chute 35 and swings at right angles to the length of the keeper 41. The latch 42 has a notch 44 adapted to interlock with the notch 45 of the keeper 41. When the latch 42 is engaged with the keeper 41, as above described, the chute 35 will be held up in a closed position, and the member 38 will be held in a depending, closed position also. The parts thus appear in Fig. 4.

The water tank 31 of the car 24 is supplied with a laterally projecting spout 46. The outer end of the spout 46 is controlled by a horizontally swinging closure 47. The closure 47 is provided on its inner face with a packing gasket 48 which, engaging the spout 46, prevents a leakage of water out of the spout. The closure 47 is hinged at 49 to the spout 46. A keeper 50 is secured to one side of the spout 46 as shown in Fig. 9. The keeper 50 has a notch 51 in its upper edge. A latch 52 is pivoted at 53 to the forward face of the closure 47, to swing vertically. When the latch 52 is swung downwardly, the same enters the notch 51

in the keeper 50, and because the notch 51 has a forward cam edge 54, adapted to co-operate with the latch, the latch will crowd the packing gasket 48 against the forward end of the spout 46 and prevent a leakage 70 as aforesaid.

A lever 55 is fulcrumed at 56 on the side of the car 24, to swing in a vertical plane. A hook 57 is pivoted to one end of the lever 55. When the latch 52 is engaged with the keeper 50, and when the member 47 is in a closed position, the hook 57 is detachably engaged beneath the free end of the latch. A depending flexible element 58 is secured to the other end of the lever 55. The lower end of the flexible element 58 is attached as shown at 59 to one of the side wings 37 of the vertically swinging chute 35 of the coal pocket 30.

The rear end of the dispensing car 24 may be provided with a hook 60 adapted to engage detachably with one end of a cable 61. The cable 61 is wound around a drum 62 including a shaft 66 journaled in a support 63 located along the right-of-way. The drum 62 may be rotated in any desired manner. In the present instance, an engine 64 is operatively connected as shown at 65 with the shaft 66 of the drum 62, in order to rotate the drum. 85

In practical operation, the latch 42 is engaged with the keeper 41. By this operation, the chute 35 and the member 38 are held closed, as shown in Fig. 4. The coal pocket 30 may then be filled with fuel. The closure 47 is swung against the outer end of the water spout 46 and the latch 52 is engaged with the notch 51 of the keeper 50, to hold the member 47 closed. The water tank 31 may then be filled through the opening 33. Fig. 6 shows the parts arranged as last above described. The hook 57 which is pivoted to one end of the lever 55 is engaged beneath the free end of the latch 52. 90

If it is desired to charge the tender 6 with coal and water, then the releasing rod 31 is raised by means of the lever 17, as shown in Fig. 8. If water and coal are not desired, then the releasing rod 31 is lowered by means of the lever 17, the handle end 19 of the lever being engaged with the upper end of the keeper 20 on the tender. 110

Let it be supposed that the releasing rod 31 is raised, as shown in Fig. 8. Then, when the tender 6 approaches the car 24, which is located adjacent the winding drum 62, the upper end of the releasing rod 21 engages the latch 42 and swings the same on its pivot 43, until the latch is disengaged from the keeper 41. The chute 35 now swings downwardly between the projections 15 and 16 on the wing 14 of the tender 6, and the projection 16, engaging one of the wings 37 of the chute 35 causes the car 24 to move along the rails 3 and 4, with the train which 120

125 130 135 140 145 150 155 160 165 170 175 180

is traversing the railroad track 1. The coal in the pocket 30 slides downwardly along the chute 35 and swings the closure 38 to a partially open position, the coal being discharged into the coal compartment 7 of the tender 6, while the latter is in motion.

- 5 When the chute 35 swings downwardly, the flexible element 58 is drawn upon, tilting the lever 55 on its fulcrum 56 and elevating the hook 57. When the hook 57 is elevated, the free end of the latch 52 is raised out of engagement with the keeper 50 on the spout 46. The closure 47, under the pressure of the water in the tank 31, swings to an open position, and water is discharged from the spout 46 within the box 68 at the rear end of the tender 6, the water flowing through the opening 10 into the water compartment 8 of the tender.
- 10 20 When the car 24 reaches the laterally inclined end 5 of the auxiliary track 3-4, the car moves, under its inertia, along the laterally deflected end 5, out of engagement with the tender 6. The cable 61 is paid off the drum 62 and engaged with the hook 60 on the dispensing car 24, and when the engine 64 is put into operation, the car may be hauled back to the place of loading. It will be obvious that, if desired, the cable 61 may 25 be engaged with the hook 60 while the dispensing car 24 is moving forwardly along with the tender 6.
- 30 Having thus described the invention, what is claimed is:—

- 35 1. In a device of the class described, a main track; an auxiliary track disposed at one side of the main track; a vehicle traversing the main track; a dispensing car traversing the auxiliary track and having 40 means for discharging laterally into the vehicle, the car being located at one side of the vehicle; a closure for said means, on the car, and controlling the lateral discharge into the vehicle; means carried by the vehicle for advancing the car with the vehicle; and means carried by the car for opening the closure.
- 45 2. A device constructed in accordance with claim 1, and further characterized by the fact that the auxiliary track includes a laterally deflected end onto which the car is

advanced by the vehicle, to free the car from the vehicle.

3. In a device of the class described, a track; a dispensing car traversing the track; a swinging chute carried by the car; a car-carried latch mechanism coöperating with the chute to maintain the same closed; a vehicle into which the chute discharges; vehicle-carried means coacting with the latch mechanism to permit a swinging of the chute; and vehicle-carried means whereby the chute engages, when the chute is swung, to advance the car along with the vehicle.

4. In a device of the class described, a track; a dispensing car traversing the track; a transversely swinging bottom closure carried by the car; a transversely swinging side closure carried by the car; 70 detachably interengaged elements on the closures, coacting to hold the closures in closed positions; a vehicle into which the car discharges when the closures are opened; vehicle-carried means coacting with one of 75 said detachably interengaged elements to secure an opening of both closures; and vehicle carried means coacting with one of the closures, when the same is in an open position, to advance the car along with the vehicle.

5. In a device of the class described, a track; a dispensing car mounted to traverse the track and having separate compartments; a bottom closure for one compartment; a side closure for the said compartment; a keeper on the side closure; a movable latch on the bottom closure and coacting with the keeper; a closure for the other compartment; a latch mechanism coacting 90 with the last specified closure to hold the same in closed position; a lever fulcrumed on the car; a connection between the lever and the latch mechanism; and a connection between the lever and the bottom closure. 95

In testimony that I claim the foregoing as my own, I have hereto affixed my signature in the presence of two witnesses.

LEO FEBRE.
